BED FOR SHOE ORNAMENTING
MACHINERY

Bismarck B. Brodfuehrer, Benjamin W. Freeman, and Charles A. Jester, Cincinnati, Ohio; said Brodfuehrer and said Jester assignors to said Freeman

Original application January 13, 1926, Serial No. 80,903, Patent No. 1,696,834. Divided and this application December 12, 1928. Serial No. 325,596

9 Claims. (Cl. 164—93)

Our invention relates to an adjustable work support of the anvil type, particularly for shoe tip presses and cut-out machines with which shoe uppers are ornamented, perforated or cut out in which the uppers are draped over the work support with parts of the upper disaligned from the plane of the supporting surface of the support. This application is a divisional of application Serial No. 80,903, filed January 13, 1926.

10 In machines for doing cut-out work and in machines for perforating and otherwise ornamenting shoe elements, the mechanical principle involved usually consists in either moving a cutting or perforating die into engagement against a shoe element or in providing a moving punch block or plunger which carries the shoe element into engagement with a cutting die, in each case the object being to cut out or ornament the shoe element with designs of the desired size and shape.

20 The particular invention disclosed herein relates to a work support for a cut-out machine such as is described and claimed in the United States patent to Freeman No. 1,681,033, of August 14, 1928.

25 In the parent case Serial No. 80,903, filed January 13, 1926, we have particularly described and claimed an adjustable work support and although the broad principle of providing an adjustable work support is covered in this parent case, there

30 are a number of improvements suggested in one particular modification which was introduced in this case which were considered of such importance as to warrant an independent divisional application thereon in which the several improvements could be more specifically disclosed and claimed.

While in the Freeman Patent No. 1,681,033 a slideable work support which is movable from work placing to operating position is shown which will permit of the draping of a closed or fitted upper around the support, no provision was made for varying the elevation of the support to permit the use of different sized and shaped dies, anvils or masks without an adjustment of the stroke of the reciprocating plunger or platen.

It is the object of our invention to provide a die supporting unit which will permit the movement of an ornamenting die from a work placing to operating position and which will be provided with means for elevating the die to a desired elevational position with reference to the pressing head. Another object is the provision of a portion of the support with a sharp edged angular ribbed upper surface which will allow the die unit ordinarily consisting of a plate with cutting dies

mounted thereon to seat in proper aligned position even though scraps or cuttings have inadvertently fallen on such upper surface.

Another object is the provision of a die support having a cooperating part which may be so connected with a fixed part of the machine frame as to provide a stop and support for an overhanging end of the die. A still further object is the provision of a guiding member for the die support which will permit the elevation of the die support but which has itself no sliding movement from work placing to work operating position.

The above and other objects to which reference will be made in the ensuing disclosure we accomplish by that certain combination and arrangement of parts of which we have shown a preferred embodiment.

In the drawing:—

Figure 1 is a side elevation of the die support.

Figure 2 is a plan view of the support.

Figure 3 is a front elevation of the die support assembly.

Figure 4 is a lateral vertical section taken along the lines 4—4 in Figure 2, with the pins 37 removed.

Figure 5 is a longitudinal vertical section taken along the lines 5—5 in Figure 2 with the pins 37 removed.

In the embodiment of our invention illustrated in Figures 1 to 5, we have illustrated a preferred type of what is known to the trade as the anvil type of bed, which provides sufficient clearance at the sides, back or front or underneath so that assembled or partly assembled uppers may be applied to the work support and the cut-out or ornamenting work may be done at a much more convenient and economical period in the construction of the shoe.

We have shown an anvil type bed 25 composed of an upper member 26 and a lower member 27 having inclined plane engaging surfaces 28. A knurled hand wheel 29 mounted on a spindle 30 rotatably journaled in the lower member 27 and fixed non-slidably thereon with a collar 30a, provides an adjustment for varying the elevation of the upper die support 26 relative to the lower member 27. The spindle 30 has a threaded portion which engages a threaded opening 31, in a boss 32, formed on the upper member. The axis of the spindle is parallel with the meeting inclined plane surfaces of the members 26 and 27 as indicated to avoid binding of the parts. This form of anvil type bed conveniently adapts itself to cut out machines in which the work is disposed on the bed, or on a die mounted on the

bed, while the bed is slidably extended to a convenient work applying position and in which the bed is then moved to operating position. Within the bed may be incorporated a guide plate 33 which engage tracks formed by upper retaining members 33a, and lower channeled portions 34 in the upper member 26. This construction assists in controlling the movement of the member 26 on the member 27. The guide plate 33 carries a guide support member 35 which serves the purpose of an additional support for the work or the die.

The upper surface of the member 26 is provided with sharp angular ribs as indicated at 40 so that when used to support a flat undersurfaced die, small chips of cut-out work or debris will be cut and fall into the grooves between the ribs so as not to interfere with the correct alignment of the die.

20 The guide plate 33 has a pair of vertically slideable pins 37 which are retained in bushings 38. The pins are threaded at their ends as indicated at 39 for mounting in threaded holes in the machine frame. While the upper member and 25 the lower member may be slideable on guide rails 36, the guide plate acts as an auxiliary guide. The guide plate 33 is, through its connection with the machine frame, fixed except for vertical movement. As channels are formed between the 30 members 33a and 34 which enclose the extended edges of the guide plate 33 the movable die supporting assembly is restrained from lateral deflections by guiding means intermediate said assembly of the relatively movable members 26 and 35 27. Thus lateral deflection is prevented in the upper member 26 by the guide plate 33. The plate 33 is itself restrained from lateral deflection by the permanently fixed pins 37 which, as has been noted, only allow vertical elevation of the 40 bushings which are permanently secured in the slide.

Extending up from the sides of the lower member 27 are the lateral guides 41 which have flanged extensions 42 which engage slanting tracks 43 in the upper member 26.

It is a particular feature of our invention that the support 26 is of maximum width to have clamped thereagainst different interchangeable dies regardless of their width and still allow closed 50 uppers to be draped thereabout or fitted uppers to be draped about its side without buckling. A die consisting of a supporting plate and with cutting instrumentalities facing upwardly may be mounted on the upper surface 40 of the upper 55 member. We refer to such a combination as a die unit. The connection between the member 26 and the die supporting plate is usually a thumb nut on a shank which engages the slot 44. The auxiliary support 35 is also medially located so that no matter how narrow the supporting plate of the die or what the arrangement of the pattern of the cutting instrumentalities, the die unit can be properly supported. Thus, irrespective of its 60 width die units are interchangeable on the support.

65 Having thus described our invention, what we claim as new and desire to secure by Letters Patent, is:—

1. A die supporting assembly for a shoe ornamenting machine having a frame, said assembly being constructed and arranged to allow a shoe upper to be draped thereabout without buckling, said assembly comprising an upper and a lower member with the upper member movable longitudinally along an inclined plane surface of said

lower member, means for adjusting the longitudinal position of the upper member relative to the lower member, and guiding means comprising a slide connected for vertical movement relative to the machine frame slidably engaging retaining means in said upper member for preventing lateral movement of said upper member during the adjustment thereof.

2. A die supporting assembly for a shoe ornamenting machine having a frame, said assembly being constructed and arranged to allow a shoe upper to be draped thereabout without buckling, said assembly comprising an upper and a lower member with the upper member movable longitudinally along an inclined plane surface of said lower member, means for adjusting the longitudinal position of the upper member relative to the lower member and having a vertically slideable connection with the machine frame and restrained

to movement at an angle to the movement of said assembly from work placing to operating position, means for preventing lateral movement of said upper member during the adjustment thereof, said assembly constructed and arranged to permit the movement of a die carried on said upper member from work placing to operating position.

3. A die supporting assembly for a shoe ornamenting machine, said assembly being constructed and arranged to allow a shoe upper to be draped thereabout without buckling, said assembly comprising an upper and a lower member with the upper member movable longitudinally along an inclined plane surface of said lower member, means for adjusting the longitudinal position of the upper member relative to the lower member, relatively fixed means at the sides of said upper member for preventing lateral movement of said upper member during the adjustment thereof, and guiding means medially of said assembly having a channeled engagement with said upper member, said means having vertically slideable retaining members.

4. A vertically adjustable die unit support for an ornamenting machine having a frame comprising upper and lower members constructed and arranged to allow clearance at the sides for receiving without buckling parts of a shoe upper, said upper member having a medially mounted guide for preventing lateral displacement of said upper member during the vertical adjustment thereof, said guide having a pin and slideable bushing connection for attachment to the frame of said machine.

5. In combination in a cut-out machine, a vertically adjustable composite base for supporting a die unit thereon, said base constructed and arranged with clearance at its sides to receive a shoe upper without buckling, and having means thereon for guiding the movement of a die unit from work placing to operating position, and relatively fixed means medially located with respect to said base and being vertically movable for preventing lateral displacement of parts of said composite base during the vertical adjustment thereof.

6. A vertically adjustable die supporting assembly for a cut-out machine for ornamenting shoe uppers, said assembly provided with an upper member having means located at its medial front corner and being of such width as to provide means for supporting, irrespective of its width, a die unit having cutting edges.

7. A die supporting assembly for a shoe ornamenting machine, said assembly being construct-

- ed and arranged to allow a shoe upper to be draped thereabout without buckling, said assembly comprising an upper and a lower member with the upper member vertically adjustable along an inclined plane surface of said lower member, means for adjusting the longitudinal position of the upper member relative to the lower member, and guiding means mounted medially of the assembly, having a channeled engagement with said upper member for preventing lateral movement of said upper member during the adjustment thereof, said upper member having medially located mounting means for the die unit and being of such width as to provide means for supporting a die unit irrespective of its width. 80
8. A die unit support having an upper face to engage a substantially flat under surface of a die unit, said face comprising alternate raised portions and depressions, the raised portions being so shaped that, under pressure of the dieing operation, they cut scraps of material which happen to be left on said face, and the depressions being adapted to receive such scraps, whereby the scraps are so disposed as to allow the die unit to seat properly on said support. 85
9. A die unit support having clearance at its sides for receiving parts of a shoe upper held on the supported die unit, without buckling said parts, and having an upper face to engage a substantially flat under surface of the die unit, said face comprising alternate raised portions and depressions, the raised portions being so shaped that, under pressure of the dieing operation, they cut scraps of material which happen to be left on said face, and the depressions being adapted to receive such scraps, whereby the scraps are so disposed as to allow the die unit to seat properly on said support. 90
